UNITED STATES PATENT OFFICE.

GEORGE M. SCHWEND, OF BIRMINGHAM, ALABAMA.

AIR-PUMP LUBRICATOR.

1,086,230.

Specification of Letters Patent.

Patented Feb. 3, 1914.

Application filed November 9, 1912. Serial No. 780,384.

To all whom it may concern:

Be it known that I, GEORGE M. SCHWEND, a citizen of the United States, and a resident of Birmingham, in the county of Jefferson 5 and State of Alabama, have invented certain new and useful Improvements in Air-Pump Lubricators, of which the following is a specification.

My invention is an improvement in air 10 pump lubricators, and has for its object the provision of mechanism for use with air pumps, wherein means is provided for throwing a charge of oil and water into the cylinder of the pump operated by the action 15 of the pump.

In the drawings: Figure 1 is a front view of the improved lubricator in connection with a pump; and Fig. 2 is a transverse vertical section.

20 In the present embodiment of the invention an outer cylindrical casing 1 is provided, having in its upper end an opening 2, which is flanged inwardly, as shown at 3, and both the opening and the flange are internally threaded, as shown in Fig. 2. The 25 casing 1 is provided in its bottom with a central nipple 4, and with other nipples 5 and 6, the said nipples being arranged on opposite sides of the nipple 4, and each of 30 the nipples 4, 5 and 6 is internally threaded at its outer end, as shown.

The inner casing 7 of cylindrical form is provided near its upper end with an annular marginal rib 8, and with an externally 35 threaded portion 9 below the rib, the said portion engaging the threads of the openings 2. The rib 8 fits against the upper end of the outer casing, and the casing 7 is provided in its lower end with a central nipple 10, the said nipple being in alinement with the nipple 4 of the outer casing. The 40 casing 7 is provided at its upper end with a central longitudinally extending neck 11, and the outer end of the neck is enlarged 45 and externally threaded, as shown at 12, and a cap 13 is threaded onto the said end of the neck. A gasket 14 is arranged between the cap and the upper end of the neck, and a valve 15 is provided fitting against the inner end of the nipple 10 for closing the said 50 nipple. The valve is provided with a stem 16, and a head 17 is secured to the outer end of the stem.

A coil spring 18 encircles the stem between 55 the head 17 and the bottom of the inner casing 7, the said stem acting normally to hold

the valve 15 closed. The head 17 is adjacent to the inner end of the nipple 4, and a pipe 19 is threaded into the outer end of the said nipple. The cylinders 20 and 21 of 60 the pumps are connected to the nipple 5 and 6 respectively, by means of pipes 22 and 23, and a check valve 24 is provided for each of the said pipes adjacent to the cylinder. The spring 18 is just strong enough to hold 65 the valve 3 closed, under ordinary conditions, to prevent the escape of the oil which is held in the casing 7, and the valve is adapted to be opened by the exhaust. The pipe 19 is connected with the exhaust. The check 70 valves 24 are arranged to prevent passage of the oil from the cylinders toward the casing 1. The oil may be inserted in the casing 7 through the neck 11, by removing the cap 13. The pipes 22 and 23 are choked at their 75 entrance to the pump cylinder so that there will be a spraying action as the oil and water enters the cylinder.

The outer casing 1 is a condensing chamber for the device, and the operation of the 80 device is as follows: In Fig. 1 the lubricator is shown in connection with the pump. The pipe 19 connected to the exhaust pipe 19 through which the steam cylinders exhaust, and the pipes 22 and 23 are connected with 85 the air cylinders 20 and 21 of the pump.

The operation of the device is as follows: At every exhaust from the engine, a portion 90 of the exhaust steam passes into the pipe 19, and this exhaust steam enters the casing 1 at the nipple 4, and impinging against the head 17, raises the said head, and opens the valve 15 to a slight extent, just sufficient to permit a portion of the oil in the casing 7 to pass out through the nipple 10. The 95 steam that enters the casing 1 at each exhaust is condensed in the said casing, and the water of condensation makes with the oil an emulsion. The said emulsion passes into the air cylinders of the pump, or is drawn 100 into the said cylinders on the downward movement of the piston. Whenever the piston of the air pump moves in one direction, a few drops of the emulsion will be drawn into the cylinder, and when the piston 105 moves in the opposite direction, the emulsion will be sprayed over the walls of the cylinder, thus lubricating the said walls and the piston.

I claim:

1. An air pump lubricator, comprising in combination with the air chamber of the

22

pumps, said chamber having a central internally threaded opening at its upper end, and having a central steam inlet opening at its lower end, and having openings at each 5 side of the inlet opening for connection with the pump cylinders, of a pipe leading from each of the said last-named openings to a cylinder, each pipe having a check valve for preventing movement of fluid from the 10 cylinder to the chamber, an oil holding chamber having an externally threaded portion for engaging the first-named opening, said chamber having a filling opening at its outer end, and a port at its inner end in 15 alignment with the steam inlet of the condensing chamber, a cap closing the filling opening, a valve within the oil chamber for coöoperating with the port to close the same, a stem connected with the valve, a head at 20 the outer end of the stem, said head being adjacent to the inner end of the steam inlet opening, and a spring encircling the stem between the head and the chamber and normally holding the valve closed.

25 2. An air pump lubricator, comprising in combination with the condensing chamber of the lubricator, said chamber having a central opening at its upper end and an inlet opening at its lower end, and being connected with the pumps, an oil holding chamber 30 received into the opening at the upper end of the condensing chamber, and having

means for preventing disengagement thereof, said chamber having a filling opening and having a port at its inner end in alignment with the inlet of the condensing chamber, and a valve normally closing the port, said valve having a head in position to be struck by the steam entering the condensing chamber whereby to open the valve. 35 40

3. An air pump lubricator, comprising in combination with the condensing chamber of the lubricator, said chamber having an opening at its upper end and an inlet port at its lower end, and being connected with the exhaust of the pump, an oil holding chamber seated in the opening at the upper end of the condensing chamber and having an outlet adjacent to the inlet of the condensing chamber, and a valve controlling 45 50 the outlet and adapted to be opened by the steam entering the condensing chamber.

4. An air pump lubricator comprising a condensing chamber having an inlet for connection with the exhaust of a pump, a chamber for holding a lubricant having an outlet adjacent to the inlet of the condensing chamber, and a valve controlling the outlet and adapted to be opened by the steam entering the condensing chamber. 55

GEORGE M. SCHWEND.
